UNITED STATES PATENT OFFICE.

ISAAC E. PALMER, OF MIDDLETOWN, CONNECTICUT.

DESIGN FOR A HAMMOCK-HOOK.

SPECIFICATION forming part of Design No. 23,349, dated June 12, 1894.

Application filed May 18, 1894. Serial No. 511,725. Term of patent 14 years.

To all whom it may concern:

Be it known that I, ISAAC E. PALMER, of Middletown, in the county of Middlesex and State of Connecticut, have invented and produced a new and original Design for Hammock-Supporting Hooks, of which the following is a specification, reference being had to the accompanying drawings, forming a part thereof.

10 The leading feature of my design is the hammock supporting hook, provided with loops spaced from one another and the point of the hook extending across the plane of the loops, as shown.

In the accompanying drawings, Figure 1 is 15 a top plan view of the hook and Fig. 2 is a view in side elevation.

A, A' represent the loops, B the point of the hook and C the shank at the bight of the hook. The shank is depressed below the 20 plane of the loops.

What I claim is—

The design for a hammock supporting hook, substantially as herein shown and described.

ISAAC E. PALMER.
